SHADOW BOX

J. C. Scott, 637 E. 43rd St., Chicago, Ill. 60653

Filed Aug. 31, 1967, Ser. No. 8,449

Term of patent 14 years

(Cl. D33—3)

FIGURE 1 is a front perspective view of a shadow box embodying my new design; the shading on the two rectangular panels and the four triangular panels indicates mirrors;

FIGURE 2 is a side elevation thereof;

FIGURE 3 is a top plan view thereof;

FIGURE 4 is a rear perspective view thereof.

I claim:

The ornamental design for a shadow box, as shown and described.
